UNITED STATES PATENT OFFICE

115,232

DESIGN FOR A BAND UNIFORM OR SIMILAR ARTICLE

Carl T. Habegger, Berne, Ind.

Application July 5, 1938, Serial No. 78,285

Term of patent 14 years

To all whom it may concern:

Be it known that I, Carl T. Habegger, a citizen of the United States and resident of Berne, county of Adams, State of Indiana, have invented a new, original, and ornamental Design for a Band Uniform or Similar Article, of which the following is a specification, reference being had to the accompanying drawing, forming a part thereof.

I claim:

The ornamental design for a band uniform or similar article, as shown.

CARL T. HABEGGER.
